CLAIM

The ornamental design for an accessory game block, as
shown and described.

DESCRIPTION

FIG. 1 is a top perspective view of an accessory game
block showing our new design;

FIG. 2 is a bottom perspective view thereof;

FIG. 3 is a top plan view thereof;

FIG. 4 is a front elevational view thereof;
FIG. 5 is a side elevational view thereof, the side oppo-
site being identical;

FIG. 6 is a bottom plan view thereof; and

FIG. 7 is a top perspective view of a modified embodi-
ment of the design shown in FIGS. 1-6.

FIG. 1

FIG. 2

FIG. 3

FIG. 6
